VANELESS DIFFUSER

Shao L. Soo, Urbana, Ill., assignor to Caterpillar Tractor Co., Peoria, Ill., a corporation of California
Filed Oct. 8, 1965, Ser. No. 494,225
3 Claims. (Cl. 230—127)

This application is a continuation-in-part of my copending application for Vaneless Diffuser, Serial No. 328,038, filed December 4, 1963, now abandoned.

The present invention relates to the diffuser section of a turbomachine, such as a compressor or turbine and particularly to an improved contour of diffuser walls for increasing the efficiency of a compressor or the like.

In the past, vaneless diffusers have been made with parallel walls, diverging walls and constant flow area configurations, without regard to specific control of boundary layer separation and attendant wall friction losses.

It is the object of the present invention to provide a vaneless diffuser specifically contoured to obtain maximum efficiency with a minimum of loss due to friction and heat.

The invention is disclosed herein in combination with a radial flow compressor but is equally useful with axial and mixed flow compressors or turbines for fluid pumping.

The manner in which the invention is carried into practice will best be understood from the following specification wherein reference is made to the accompanying drawings.

In the drawings:

FIG. 1 is a central sectional view through a typical radial compressor and diffuser therefor showing a diffuser embodying the present invention;

FIG. 2 is a fragmentary view in section showing a modified diffuser profile;

FIGS. 3 to 6, inclusive, are schematic views illustrating typical flow patterns of fluid through a confined space such as a diffuser; and

FIG. 7 is an enlarged view in cross section of the diffuser profile of FIG. 1 showing flow patterns at different positions therein.

FIG. 8 is a graph of boundary layer parameter G as a function of boundary layer parameter Γ_r .

The compressor shown in FIG. 1 includes a housing 10, a shaft 12 driven by means not shown to rotate an impeller 14 thereon, the impeller having blades 15. Fluid to be compressed enters the housing axially of the shaft from the left as shown in FIG. 1 and is compressed by the impeller and directed radially outwardly at its periphery through an annular vaneless diffuser consisting of a pair of axially spaced annular walls shown at 16 in FIG. 1 into a collector, 17. In FIG. 1 both walls of the diffuser are contoured according to the teaching of the present invention. A modification is shown in FIG. 2 where a similar diffuser is shown as having one flat wall and the other wall contoured to obtain a similar result.

The present invention is predicated upon producing a diffuser profile by applying known formulae to produce a condition of optimum flow throughout the greater part of its length. The efficiency of fluid flow through a confined space is determined largely by boundary layer conditions for the action of the fluid adjacent the walls of the space. Some boundary layer conditions are illustrated in FIGS. 3 to 6, inclusive, which show velocity profiles of a fluid flowing within passage walls. As shown in FIGS. 3, 4 and 5, the flow at the main or central portion of the fluid stream is relatively uniform, while the boundary layer or flow adjacent the passage walls varies considerably under different conditions of velocity, pressure, temperature, density and other factors.

2

Under certain conditions, there exists an unseparated boundary layer having a velocity gradient adjacent to the walls of less than 90° as illustrated in FIG. 4. This produces high friction and conversion of kinetic energy to heat. FIG. 5 represents a condition producing a separated boundary layer where there is a greater than 90° gradient and a reverse curve in the velocity profile. This reverse curve is shown by the enlargement in FIG. 6 illustrating the reversal of flow in the velocity profile and representing an even greater loss in efficiency and flow range than the condition illustrated in FIG. 4.

The optimum conditions are represented in FIG. 3 which illustrates imminent boundary layer separation with a gradient adjacent the wall of approximately 90° .

The present invention resides in the provision of a diffuser which produces the efficient velocity profile of the type illustrated in FIG. 3 throughout the greater part of its length. This is accomplished through a converging-diverging-converging diffuser wall contour as represented by the areas 18, 19 and 20 of FIG. 7.

A first area represented by the distance 18 in FIG. 7 has an entry portion of converging cross section which is provided to produce acceleration up to the point of a throat, indicated at 21, which acceleration reduces turbulence created by the vanes 15 of the compressor. A second area 19 has a diverging cross section and causes diffusion up to the point 22 where imminent boundary layer separation is reached. In communication with and extending downstream from this point and to the point of discharge as represented by a third area 20, the walls of the diffuser are contoured to maintain imminent boundary layer separation as represented by the three typical velocity profiles 25, 26 and 27 illustrated in this area.

The following presents one application of known formulae to illustrate the detailed computation procedure followed in producing the diffuser profile for optimum flow. Other procedures could be followed to produce similar profiles.

A. Nomenclature

The location in the diffuser passage is specified by the cylindrical coordinates r , θ , and z with corresponding mean velocity components u , v , and w . Free stream conditions, outside the wall boundary layers, are noted by the absence of subscripts; conditions within the boundary layers are noted by subscript B; wall conditions are noted by subscript w; and free stream inlet conditions are noted by subscript 1. The fluid properties are:

50 Pressure, p
Density, ρ
Temperature, t
Dynamic viscosity, μ
Kinematic viscosity, ν
55 Boundary layer thickness, δ
Turbulent radial wall shear stress, τ_r
Radial Mach number, M_r

B. Equations of fluid mechanics

60 Beginning with the Navier-Stokes equations and the equation of conservation of mass in cylindrical coordinates, the assumptions of steady, compressible, axisymmetric, boundary layer flow results in the following momentum integral equation:

$$\frac{\tau_r}{\rho u^2} = \frac{\theta_r}{u} \frac{du}{dr} (2 + H_r - M_r^2) + \frac{d\theta_r}{dr} + \frac{\theta_r}{r} \left[1 + M_r^2 \left(\frac{v}{u} \right)^2 - \left(\frac{v}{u} \right)^2 \frac{\delta \theta^* + \theta_r}{\theta_r} \right] - \quad (1)$$

where

$$\begin{aligned} H_r &= \frac{\delta_r^*}{\theta_r} \\ &= \int_0^{\delta} \left(1 - \frac{\rho_B u_B}{\rho u} \right) dz \\ &= \int_0^{\delta} \frac{\rho_B u_B}{\rho u} \left(1 - \frac{u_B}{u} \right) dz \\ &= \int_0^{\delta} \left(1 - \frac{\rho_B v_B}{\rho v} \right) dz \end{aligned}$$

and

$$\theta_r = \int_0^{\delta} \frac{\rho_B v_B}{\rho v} \left(1 - \frac{v_B}{v} \right) dz$$

Extending the well-known method of Buri for two-dimensional incompressible flow, the following is derived from Equation 1:

$$\frac{dY_r}{dr} + \frac{5}{4} \frac{Y_r}{r} \left[1 + \left(\frac{v}{u} \right)^2 G \right] = \frac{\rho_w F}{\rho} \quad (2)$$

where

$$\begin{aligned} Y_r &= \theta_r \left(\frac{u \theta_r}{v} \right)^{1/4} \\ G &= \frac{9}{5} + H_r - \frac{\theta_r}{\theta_r} - \frac{\delta_r^*}{\theta_r} \\ F &= .017 \frac{\rho}{\rho_w} - 5.15 \Gamma_r + 1.075 M_r^2 \Gamma_r \end{aligned}$$

and

$$\Gamma_r = \frac{\rho}{\rho_w} Y_r \left[\frac{1}{u} \left(\frac{du}{dr} \right) - \frac{1}{r} \left(\frac{v}{u} \right)^2 \right]$$

Upon inserting the definition of Γ_r in Equation 2 a linear equation of first order in Y_r results:

$$\begin{aligned} \frac{dY_r}{dr} + \left[\frac{5}{4} \frac{1}{r} \left(1 + \left(\frac{v}{u} \right)^2 G \right) + 5.15 \left(\frac{1}{u} \frac{du}{dr} - \frac{1}{r} \left(\frac{v}{u} \right)^2 \right) + \right. \\ \left. 1.075 M_r \left(\frac{1}{u} \frac{du}{dr} - \frac{1}{r} \left(\frac{v}{u} \right)^2 \right) \right] Y_r = .017 \end{aligned} \quad (3)$$

Integration of Equation 3 yields, in terms of Γ_r :

$$\Gamma_r = \frac{\rho}{\rho_w} \left[\frac{1}{u} \frac{du}{dr} - \frac{1}{r} \left(\frac{v}{u} \right)^2 \right] \left[.017 \int_{r_1}^r r^{1.25} u^{5.15} e^{\alpha} dr + K \right] \quad (4)$$

where

$$\alpha = \int_{r_1}^r \left(\frac{v}{u} \right)^2 (1.25 G - 5.15) \frac{dr}{r} + 1.075 \left[\int_{r_1}^r M_r^2 \left(\frac{v}{u} \right)^2 dr \right] - \int_{r_1}^r M_r^2 \frac{1}{u} \frac{du}{dr} dr \quad (5)$$

and K is a constant of integration.

C. Diffuser profile

The solution of Equation 4 may be obtained by specifying u , v , and G as functions of r and performing the required integrations. Constant K may be obtained by specifying a certain value of Γ_r at $r=r_1$.

As an example, let u be given by:

$$u = u_1 \frac{\rho_1}{\rho} \frac{r_1}{r} \frac{L_1 - 2\delta_{r_1}^*}{L - 2\delta_r^*} \quad (\text{conservation of mass})$$

where L is the diffuser wall spacing. Let v be given by:

$$v = \frac{r_1 v_1}{r} \quad (\text{free-vortex})$$

G may be taken from FIG. 8. At a specified r , trial and error yields Γ_r for specified L . Using Buri's data, Γ_r is restricted to the range:

$$\begin{aligned} \Gamma_{r \text{ max.}} &= .0033 & (\text{stagnation}) \\ \Gamma_{r \text{ min.}} &= -.06 & (\text{separation}) \end{aligned}$$

The diffuser profile illustrated in FIG. 7 may be obtained by specifying the wall spacing L in region 18 in accordance with the following equations:

$$L = \frac{r_1 L_1}{r} \left[1 + \frac{1}{\sqrt{2}} \frac{\tan \gamma}{\sin^{3/2} \Delta_1} \frac{r - r_1}{\sqrt{r_1 L_1}} \right]^2 \quad (5)$$

where, from NACA Technical Note 1426,

$$\tan \gamma = \sqrt{2} \sin^{3/2} \Delta_1 \frac{\sqrt{r_1 L_1}}{r_{21} - r_1} \left[\left(\frac{r_{21} L_{21}}{r_1 L_1} \right)^{1/2} - 1 \right] \quad (6)$$

and

$$\tan \Delta_1 = \frac{u_1}{v_1}$$

r_{21} =radius to throat 21

L_{21} =wall spacing at throat 21

The dimensions r_{21} and L_{21} are given by the required design conditions of the diffuser, such as design mass flow and pressure ratio.

The diffuser profile in region 19 may also be portioned in accordance with NACA Technical Note 1426, as follows:

$$L = \frac{r_{21} L_{21}}{r} \left[1 + \frac{1}{\sqrt{2}} \frac{\tan \psi}{\sin^{3/2} \Delta_1} \frac{r - r_{21}}{\sqrt{r_{21} L_{21}}} \right]^2 \quad (6)$$

where ψ may vary between 4 and 10 degrees.

Calculation of L in region 19 is terminated when Γ_r , Equation 4, reaches the imminent separation value of approximately $-.055$. The wall spacing in region 20 is computed by keeping $\Gamma_r = -.055$ =constant so as to maintain imminent boundary layer separation to the diffuser discharge.

The above example is presented as an illustration only. Other procedures could be used to obtain the non-separating vaneless diffuser shape shown generally by FIG. 7. The diffuser flow could be unsteady or non-symmetric. The boundary layers could be laminar as well as turbulent. The flow could be axial, as the discharge from an axial turbine, or at any intermediate angle with respect to the shaft 12.

I claim:

1. A vaneless diffuser for a radial flow turbomachine, said diffuser comprising a pair of axially spaced annular walls about the periphery of an impeller and defining a vaneless diffuser flow passage thereabout, the radially inner portion of the axially spaced walls defining an entry portion for pumped fluid to said diffuser passage, the radially outer portion defining a discharge point where in said pumped fluid enters a surrounding collector in an unrestricted manner, said walls of said entry portion defining a first converging area to a throat for accelerating fluid and reducing turbulence in the fluid flow, said axially spaced walls defining a diverging second portion of said flow passage to define an area of increasing cross-section to a point in the downstream flow where boundary layer separation is imminent from said axially spaced walls in said second portion of said flow passage, said axially spaced walls defining a third portion of said flow passage in communication with said second portion and extending downstream of said second portion of said flow passage to the point of discharge therefrom, said axially spaced walls of said third portion defining a means for maintaining the condition of im-

minent boundary layer separation from said walls throughout the third portion of said flow passage.

2. A vaneless diffuser for a radial flow turbomachine according to claim 1 wherein said axially spaced annular walls are arranged symmetrically about a plane midway between said walls. 5

3. A vaneless diffuser for a radial flow turbomachine according to claim 1 wherein one of said axially spaced annular walls is substantially flat.
